(57) **CLAIM**

We claim the ornamental design for a outer surface of a casserole, as shown and described.

DESCRIPTION

FIG. 1 is a perspective view of an outer surface of a casserole according to the new design;

FIG. 2 is a side elevation view of one side of the outer surface of the casserole shown in FIG. 1, the other side being identical thereto;

FIG. 3 is a front view of the outer surface of the casserole shown in FIG. 1, the rear view being identical thereto;

FIG. 4 is a top view of the outer surface of the casserole shown in FIG. 1;

FIG. 5 is a bottom view of the outer surface of the casserole shown in FIG. 1;

FIG. 6 is a perspective view of another preferred embodiment of a casserole according to the new design;

FIG. 7 is a side elevation view of one side of the outer surface of the casserole shown in FIG. 6, the other side being identical thereto;

FIG. 8 is a front view of the outer surface of the casserole shown in FIG. 6, the rear view being identical thereto;

FIG. 9 is a top view of the outer surface of the casserole shown in FIG. 6; and,

FIG. 10 is a bottom view of the outer surface of the casserole shown in FIG. 6.

Features shown in broken lines in the drawings are not part of the claim.
